UNITED STATES PATENT OFFICE.

JAMES GAGE BAILEY, OF NEW GLASGOW, NOVA SCOTIA, CANADA.

HARROW.

SPECIFICATION forming part of Letters Patent No. 394,809, dated December 18, 1888.

Application filed February 11, 1888. Serial No. 263,692. (No model.)

To all whom it may concern:

Be it known that I, JAMES GAGE BAILEY, a subject of the Queen of Great Britain, residing at New Glasgow, in the county of Pictou 5 and Province of Nova Scotia, Canada, have invented certain new and useful Improvements in Harrows; and I do hereby declare the following to be a full, clear, and exact description of the invention, such as will enable others 10 skilled in the art to which it appertains to make and use the same.

My invention relates to spring-tooth harrows, and especially to the means employed for attaching the teeth to the harrow-frame. 15 The object of my invention is to provide a more cheap, durable, and simple seat or saddle for the teeth, which saddle shall be so arranged that the operation of bolting the tooth to the frame and adjusting it upon the seat 20 can be performed with greater facility.

A further object of my invention is to provide means for indicating and measuring the depth to which the tooth may be adjusted.

With these ends in view my invention consists in the peculiar features and combinations of parts more fully described herein-after, and pointed out in the claims.

Referring to the accompanying drawings, Figure 1 represents a sectional elevation of 30 my complete device, the seat being in rigid adjustment at the intersection of the cross-bars forming the harrow-frame; Fig. 2, a sectional end view; Fig. 3, a top view of the seat without the tooth; Fig. 4, a bottom view; Figs. 35 5 and 6, sectional elevations of modifications; Fig. 7, a top view of the seat and tooth, showing division marks or graduations for grading the depth of the tooth to any desired measurement; Fig. 8, an additional modification of 40 the bolt for fastening the seat to the frame, and Fig. 9 a detail of the modified bolt.

The reference-letters *aa'* indicate a pair of cross-bars forming the main framing of the harrow, and which are provided with longitudinal flanges *k*, extending along their opposite edges and above and below their central portion, thereby having the general outline of a T-rail. The construction of these cross-bars, however, does not form the novel 50 feature of this invention, as they have been shown and described in my previous patent.

The seat *b* is rigidly fastened to the cross-

bars by the bolt *c*, which passes through the cross-bars and binds them together in the usual manner. The seat is made of cast metal, 55 which is, by preference, cast around the head of the bolt *c* and holds the bolt rigidly in place, as will be seen in Fig. 1. The seat *b* is provided with an interior recess or chamber, *d*, which is given, preferably, the form of a 60 segment of a circle, although the other forms shown in the modifications could be successfully employed. In the upper wall of this chamber is made an oblong slot, *e*, through which passes the tooth-bolt *f*. The width of 65 this oblong slot *e* is less than the diameter of the head *m* of the tooth-bolt, so as to retain it within the slot.

For the purpose of inserting and removing the bolt *f*, a transverse slot or enlargement, *g*, 70 is formed at one extremity of the oblong slot *e*, as will be more clearly seen in Figs. 2 and 3. The upper edges of the seat are provided with the usual lips, *h*, to prevent lateral play of the tooth, and the bottom of the seat is 75 provided with diagonal embossment *i*, which fits between the upper flanges of the cross-bars and supplies the place of the seat-blocks which have heretofore been interposed between the seat and bar. This embossment *i* 80 will always keep the seat locked in its proper diagonal position in relation to the cross-bars.

The tooth-bolt is provided with a nut, *n*, by which the tooth is secured to the seat, so that by tightening or loosening this nut the tooth 85 can be shifted upon its seat. The frame-bolt *c* passes down through the cross-bars and block *o*, which is interposed between the bars, and the seat and bars are drawn rigidly together by means of the nut *p* upon the lower end of 90 the bolt. The heads of the bolts *f* and *c* face each other, and their threaded ends extend in substantially opposite directions.

In the modification illustrated in Fig. 5 the tooth-seat is provided with a concave upper 95 surface for the reception of the tooth, and the shape of the internal chamber is considerably changed, and in the modification illustrated in Fig. 6 this bearing-surface is shown straight and slanting obliquely, both of which forms 100 can be resorted to without departing from the scope of my invention. While it is thus shown to be immaterial as to the precise construction of the chamber within which the head of

the tooth-bolt operates, yet it is desirable that the upper wall of the chamber should correspond with the exterior surface upon which the tooth-shank *r* bears, for the purpose of facilitating the adjusting operation of the tooth.

In order to measure the depth to which each tooth is extended downward, I provide the tooth and seat with graduations or divisions *t*, forming a scale, as will be more clearly shown in Fig. 7. By this means the teeth can all be readily set in uniform adjustment or set at various depths, as circumstances may require.

It is not absolutely essential that the tooth itself should be provided with divisions adapted to register with those on the seat, as the depth of the tooth can be easily determined by the position of the end of the shank.

Instead of casting the seat around the head of the frame-bolt *c*, the seat could be provided with a bolt-hole and the bolt with a T-head. The bolt could then be passed down through the oblong slot and through the hole in the bottom of the seat and the bolt-head turned transversely to the slot, in which position it would not jump out of the seat, and it could then be removably secured in place, as will be more clearly seen in Figs. 8 and 9. In Fig. 8 dotted lines represent the bolt with its head turned transversely to the slot.

The construction of my device having been set forth, its operation will be briefly described by stating that after the seat has been rigidly fastened to the cross-bars *a a'* by the bolt *c* and nut *p* the tooth-bolt *f* is next inserted into the oblong slot *e*, and the shank *r*, which is provided with usual bolt-hole, is placed over the upwardly-projecting end of the bolt. The nut *n* is then applied and the shank of the tooth securely fastened down upon the seat. When it is desired to shift the tooth upon its seat for the purpose of raising or depressing the point of the tooth, this operation can be easily performed by simply unscrewing the nut, which will allow the shank *s* to slide over the face of the seat with facility. When it is desired to remove the tooth-bolt, it can be done by simply removing the nut *n* and tooth from the seat, then tilting the bolt over to one side, and at the same time lifting its head out through the transverse slot *g*. Thus it will be seen that the head of the bolt is loosely confined within the interior chamber and has a free lateral movement to adapt itself to the various adjustments of the tooth.

At whatever depth the tooth may be adjusted

the divisions upon the seat will indicate the amount.

It is obvious that many slight changes in the construction and operation of my invention might be resorted to without departing from the spirit and scope of my invention. Hence I wish it understood that I do not limit myself to the precise construction herein shown, but feel entitled to all such changes as come within the scope of my invention.

What I claim as new, and desire to secure by Letters Patent, is—

1. A harrow-tooth seat provided with an interior chamber having a slot extending into it, in combination with a bolt the head of which is loosely confined within said chamber, substantially as set forth.

2. A harrow-tooth seat having an interior chamber or cavity provided with an oblong slot, in combination with a tooth and a fastening-bolt passing through said slot and retained therein, substantially as described.

3. In combination with a harrow-tooth and fastening-bolt, a seat provided with a cavity or chamber having a contracted oblong slot through which said bolt passes, whereby the head of the bolt is retained within said cavity or chamber, substantially as described.

4. A tooth-seat having an internal cavity provided with an oblong slot having a transverse enlargement, whereby the tooth-bolt is adjustably and removably secured to the seat, substantially as described.

5. The combination, in a harrow, of a seat having an interior chamber provided with an oblong slot, a bolt passing through the same and having its head adjustably confined within said chamber, a tooth bearing upon said seat and secured thereto by said bolt, and a bolt extending from the under side of said seat through cross-bars to which the seat is fastened, all arranged and adapted to operate as described.

6. In a harrow, a tooth-seat provided with bolts having their heads secured in the seat and their shanks projecting in substantially opposite directions through the frame and tooth, respectively, as set forth.

In testimony whereof I affix my signature in presence of two witnesses.

JAMES GAGE BAILEY.
